UNITED STATES PATENT OFFICE

ABNER E. CALLISON, OF NEW YORK, N. Y.

AEROPLANE CONSTRUCTION

Original application filed November 11, 1925, Serial No. 68,271. Divided and this application filed September 16, 1926. Serial No. 135,732.

The present invention relates to transportation by means of aeroplanes and deals particularly with improved constructions which adapt the transporting means to carry freight with greater ease of loading and unloading.

The present application is a division of the application filed by the present inventor for "transportation system", Serial No. 68,271 filed November 11, 1925.

An object of the invention is the adaptation of an airship of what is commonly termed the lighter-than-air type, for the reception of the containers, the invention relating particularly to the means for hoisting the container into the interior of the ship and the means for securing the containers in place with provision for quickly releasing the containers in case of emergency. The frame work of dirigible airships contains many spaces therewithin which are not required for the gas cells. It is proposed to adapt these unused spaces for the reception of the containers. More particularly a hatchway may be provided in the lower part of the outer surface of the airship through which access may be had to the interior of the frame and above the hatchway a mono-rail may be carried with the interior frame work upon which may travel suitable trolley carriers supporting at all times the containers and capable of being fixed in position, if desired. In the event of emergency it may be found necessary to lighten the airship. For this purpose suitable releasing devices may be provided which will instantaneously release the lifting bales from the overhead support and allow the container to fall through the outer covering of the airship.

The invention has for a further object to adapt aeroplanes to the transportation of the container. It may be found preferable to load the container through the front end of the fuselage and to this end it is contemplated forming the tapering front end of the fuselage into separable sections, which, when separated disclose a space for the reception of the container. If desired, in the interest of a reduction in weight, no covering need be provided for the walls of the fuselage

forming the cargo space, the sides of the container serving to continue the stream line form of the fuselage with yielding means to engage the container and form weather proof joints. Suitable securing devices are also contemplated which will rigidly secure the container within the cargo space. The container according to the present invention is particularly applicable for this purpose since the sliding doors in the one end thereof may be disposed adjacent the space for the operator whereby easy access may be had.

Figure 1 is a view in side elevation showing one type of aeroplane in which the container may be carried.

Figure 2 is a view in end elevation showing the aeroplane and the doors at the forward end thereof in closed position.

Figure 3 is a view similar to Figure 2 but showing the doors in open position and a container within the cargo space of the aeroplane.

Figures 4 and 5 are fragmentary detail views showing the means for supporting the container within the cargo space of an aeroplane and the means for securing the container in position.

Figure 6 is a detail view looking from above and showing fragmentary portions of the cargo space and container.

Figure 7 is a fragmentary view showing the structure disclosed at the left hand side of Figure 6 but looking from the side of the aeroplane.

Figure 8 is a view in side elevation of another modification of an aeroplane according to the present invention adapted to receive the container through a side of the fuselage.

As has been pointed out hereinbefore the invention also contemplates the transfer of one of the containers in heavier-than-aircraft. The cargo space in an aeroplane adapted to receive a container according to the present invention is illustrated in Figures 1 through 7. The fuselage of an airship is indicated at *i* supported upon the wings *i'* and propelled by spaced motors *i''* disposed respectively upon opposite sides of the fuselage. The container is adapted to be loaded into the plane from the front end of the

fuselage and to this end the stream-line front-end of the fuselage is formed as a pair of sliding doors i^3 shown in closed position in Figure 2 and in open position in Figure 3. In Figure 3 the container is illustrated within the cargo space which need not be formed with top, bottom or side walls, the walls of the container being relied upon to provide the continuation of the stream-line effect and suitable yielding sealing devices being provided to engage the ends of the container to insure a weather tight joint. The stream line front end of the fuselage is formed as a pair of sliding doors i^3 shown in closed position in Figure 3. Vertical frame members which are preferably angle pieces are indicated at i^7 which are spaced from one another as seen in Figure 1. Secured to the frame members i^7 near the lower part of the cargo space is a supporting member in the form of an angle member i^8 which serves as a track for the wheels e^3 to support the container within the cargo space. Rearwardly of the cargo space and above the track i^8 there is formed a plate i^9 beneath which the protruding edge of the container formed by the angles a^5 and a^6 is adapted to slide and be engaged thereby to rigidly retain the container in position. The cargo space is also formed adjacent the end of the floor of the fuselage with a yielding buffer q^9 which serves not only as means to absorb shocks caused by or incident to the loading of the container within the cargo space but which also seals the floor of the fuselage with respect to the bottom of the container. Access to the cock pit of the aircraft is afforded through a door in the side thereof indicated in general at q^2 which may be formed to pivot about the point i^{10} and which may extend beyond the point of the pivot as at q^{2x} to be formed at the outer end thereof with a yielding buffer member q^{2y} to engage the corner of the container a to form a substantially air tight joint and continue the wall of the fuselage as will be understood.

To secure the container within the cargo space suitable locks j are illustrated. These locks preferably take the form of an arm j having a downwardly bent portion j' formed with an enlarged head j^2 to engage a key-hole slot a^{20} formed in the front extended portion a^{21} of the floor a' . The arm J is slidably mounted in a carrier j^3 pivoted as at j^4 to upright members i^5 of the fuselage and adapted to swing from a position without the fuselage to operative position indicated in Figures 4, 5 and 6. The downwardly extended portion j' is adapted to enter the key-hole slot and is then retracted by means of the hand wheel j^6 engaging the threaded end j^8 of the rod j .

In order to seal the upper part of the cargo space and also to provide bracing means for the top of the container a swinging frame

is provided shown in Figures 4 and 5. Pivoted at suitable points to an angle piece i^{11} carried with the vertical members i^{7x} of the fuselage are arms i^{12} , which are pivoted at their lower ends to a slotted member formed conveniently of angle pieces i^{13} and i^{14} forming therebetween a slot i^{15} for the reception of a bracing member i^{16} . This bracing member is secured to a slide i^{17} which is slidable between adjacent sides of angle pieces i^{7x} , Figure 5 and at its rear end the bracing member is turned down as at i^{18x} to form a cut-out portion to engage the front and side walls of the corners of the containers a . Immediately above the slide i^{16} and secured as by rivets to the angle piece i^{14} is a cover member of light sheet metal i^{18} adapted to extend forwardly of the cargo space and overlie or, if desired, underlie the front closure section i^{11} to seal the joint therebetween to give a stream line effect and prevent the entrance of rain etc. within the cargo space. When the container is in course of loading within the cargo space, the brace member i^{16} is raised in the following manner: A reach rod i^{19} is secured to the angle piece i^{13} , Figure 5, and extends rearwardly to the pilot seat. By pulling the reach rod i^{19} rearwardly the slide i^{17} is drawn rearwardly and upwardly by reason of the pivoted connection between the arms i^{12} and angle i^{11} which causes the bracing member i^{16} to be raised; but inasmuch as the bracing member i^{16} is rigidly secured to the slide i^{17} as by means of the angle piece i^{17x} riveted to the brace i^{16} and to the slide i^{17} the brace i^{16} is only permitted a vertical movement sufficient to raise it out of the way of the bale a^{15} until the container is in place within the cargo space after which the reach rod is pushed forwardly and the brace i^{16} allowed to lower in engaging position with the front edge of the container a . To secure the container within the cargo space suitable locks are illustrated. These locks preferably take the form of an arm j having a downwardly bent portion j' formed with an enlarged head j^2 and slidably mounted in a carrier j^3 pivoted as at j^4 to an upright i^5 and adapted to swing into operative position shown in Figure 4. The downwardly extending portion j' is adapted to enter a slot such as a key-hole slot formed in the upper flange of the I-beam A^2 and is then retracted within the slot by means of the hand wheel or nut j^6 engaging the threaded nut j^8 of the rod j . The wheels e^3 of the container may, if desired, rest upon an angle piece i^8 carried in the bottom of the fuselage.

As shown in Figures 1 and 8, the plane has a platform q^4 and steps q^5 , all within the fuselage, and an opening q^6 in the upper part of the fuselage is provided to give ready access to the platform from above. This enables an attendant to receive containers from

other ships in flight and to facilitate the transfer of cargo from one plane to another.

The planes may be equipped in addition with a reel and cable ⁷⁴ by which articles may be lowered from the plane to a receiving plane.

In order to enable the pilot to position the plane properly, a telescope ⁷² is provided in the floor of the plane, and a mirror ⁷³ enables him to sight through the telescope with ease.

Figure 8 illustrates a modification of the plane indicated in Figures 1 to 3 wherein a single propelling motor centrally of the fuselage is availed of. In this instance, provision is made for placing the container ¹⁵ *a* within the fuselage through the side thereof. Thus a pilot may be seated forwardly of the cargo space while a mail clerk may occupy a compartment rearwardly of the container ²⁰ *a*.

The above serves as an illustration of various ways in which this invention may be employed but it is understood that other designs may be employed without departing from the scope of this invention, as outlined in the appended claims.

What is claimed is:

1. In an aeroplane whereof the fuselage is formed with a cargo space, means of access to the cargo space, locking means for the container within the cargo space, comprising a bearing member pivoted outwardly of the fuselage, a relatively movable hook-member to engage a key-hole slot formed in the container, and means to move the hook member relative to the bearing member.

2. In an aeroplane whereof the fuselage is formed with a cargo space, a container carried in the space, and means to secure the container to the fuselage, said means including means for bracing the fuselage structure.

3. In an aeroplane whereof the fuselage is formed with a cargo space, means of access to the cargo space, comprising a sectional front end of the fuselage, means to move the sections with respect to one another to expose the cargo space and sealing and bracing means within the cargo space.

4. In an aeroplane whereof the fuselage is formed with a cargo space formed with an opening, a closure for said opening, a brace supporting member capable of arcuate movement within the cargo space, a bracing member for a container supported in the brace supporting member, and means to limit the movement of the bracing member in a vertical direction.

5. In an aeroplane whereof the fuselage is formed with a cargo space formed with an opening, a closure for said opening, a brace supporting member capable of arcuate movement within the cargo space, a bracing member for a container supported in the brace supporting member, means to limit the move-

ment of the bracing member in a vertical direction, and a sealing member carried with the brace supporting member and adapted to lie in overlapping relationship with the closure.

70

6. In an aeroplane construction, a cargo space, means of access from the fuselage to the cargo space, seating means in the fuselage to receive the operator, a freight platform in the fuselage independent of the operators' seat, and means of access from the platform to the cargo space, the top of said fuselage being formed with an opening immediately above the platform.

75

7. In an aeroplane whereof the fuselage is formed with a cargo space formed with an opening, a closure for said opening, a brace supporting member capable of arcuate movement within the cargo space, and a bracing member for a container supported in the brace supporting member.

80

8. A structure of the kind described comprising a fuselage having end doors, a bottomless chamber behind the doors, and a freight carrying container fitting the chamber of the fuselage and with the bottom of the container forming the bottom of the chambered part of the fuselage.

85

9. An air craft having a fuselage with a chamber therein open at the front and bottom of the fuselage, a container fitting in the chamber and with the bottom of the container forming the bottom of the corresponding part of the fuselage, and means operable from the exterior of the fuselage for fastening the bottom part of the container to the fuselage.

95

10. An air craft having a fuselage with a chamber therein open at the front and bottom of the fuselage a stiffening frame at the lower sides of said chamber, a container having lower sides fitting against said stiffening frames and with a bottom forming the bottom of the chamber and corresponding part of the fuselage, and means for fastening the lower sides of the container to said stiffening frames.
